ELECTRIC SWITCH

William C. Strungart, Kalamazoo, Mich.

Application December 29, 1938, Serial No. 248,322

8 Claims. (Cl. 200—33)

This invention relates to an improved electric switch provided with a time delay attachment for maintaining a circuit around the switch for a predetermined period after the circuit through the switch has been broken.

It is an object of this invention to provide an improved manually operated switch adapted to be pivotally mounted for a rocking motion to move a sliding contact member relatively to two stationary contacts or terminals for making and breaking a circuit therethrough, and a secondary switch connected to said stationary contacts and pivotally mounted to move as a unit with said first mentioned switch and provided with means whereby a circuit will be completed around said slidably mounted contact and maintained for a predetermined period after said sliding contact has been moved to an open position.

More particularly, it is an aim of this invention to provide a time delay attachment comprising a pivotally mounted container having a perforated transverse wall and adapted to contain an electrolyte substance forming a conductor between two electrodes extending into one end of said casing to maintain a circuit therethrough for a predetermined period until said substance can seep through the perforations of said wall and out of the end of the casing in which said electrodes are disposed.

Still a further aim of the invention is to provide means adapted to enclose the exposed ends of a pair of electrodes to prevent sparks when a circuit is completed or broken between said electrodes by an electrolyte conductor.

Still a further aim of the invention is to provide a switch provided with a time relay attachment, of simple construction capable of being economically manufactured and of operating with a maximum of efficiency.

Other objects and advantages of the invention will hereinafter become more fully apparent from the following description of the drawings, which illustrate a preferred embodiment thereof, and wherein:

Figure 1 is a top plan view of the switch shown mounted in a container with the lid thereof in an open position.

Figure 2 is a vertical sectional view taken along the line 2—2 of Figure 1, with the lid in a closed position.

Figure 3 is a longitudinal vertical central sectional view of the switch, including the time delay attachment, in an open position.

Figure 4 is a view similar to Figure 3 showing the switch in its closed position.

Figure 5 is a view similar to Figure 3, showing the switch in an open position and the time delay attachment in a closed position.

Figure 6 is a transverse vertical sectional view taken along the line 6—6 of Figure 5.

Figure 7 is a diagrammatic view showing the invention in circuit with a source of electric current and a light bulb, and

Figure 8 is an enlarged central vertical sectional view partly in elevation of the terminal 10 end of one of the electrodes.

Referring more particularly to the drawings, wherein like reference characters designate like or corresponding parts throughout the different views, 10 designates generally a box or container in which the switch may be mounted and which is provided with a lid 11 which is hinged at 12.

A pair of spaced standards 13 project upwardly from the bottom of the box 10 to provide supporting means for the switch. An elongated casing 14 is provided with the stub shafts 15 which project outwardly from opposite sides thereof and intermediate of its ends, and which are adapted to extend through openings in the free ends of the standards 13 to pivotally mount the casing 14.

Casing 14 is provided with a transverse partition 16 dividing the corresponding ends of said casing into corresponding chambers 17 and 18. Partition 16 is provided with an opening 19 adjacent its bottom and with an opening 20 adjacent its top. Casing 14 is provided with the cover 21 which is sealed to the sides as indicated at 22 to provide a liquid and airtight closure.

A cylindrical casing 23 of insulating material is supported by means of the beam 24 in an elevated position above the lid 21 and is disposed longitudinally thereof. Member 23 has a stationary contact 25 mounted in one end thereof and provided with a reduced threaded shank projecting outwardly therethrough and provided with a nut and washer to form a terminal post designated 26. A second stationary contact, designated generally 27, is mounted in the opposite open end of the member 23 and is likewise provided with a corresponding terminal post 26.

Contact 27 includes a tubular portion 28 which is connected at one end to its post 26 and which extends substantially through the cylindrical member 23 with its free end slightly spaced from contacts 25.

Loosely mounted in the tubular portion 28, which as illustrated comprises a plurality of metal rods each of which are of a length less than that of the tubular portion 28 but substantially greater than 55

the space between the free end of the tubular portion 28 and the contact 25 so that one or more of said rods will engage contact 25 when the switch is in position as seen in Figure 4 to thereby complete contact between the two posts 26. When the switch is tilted in the opposite direction each of the rods comprising the movable contact 29 will be in a retracted position within the tubular portion 28 and spaced from contact 25, as seen in Figures 3 and 5, to open or break the contact between the two terminal posts 26.

A lead wire 30, as best seen in Figure 1 and in the diagrammatic view Figure 7, extends from the post 26 of contact 25 to a post 31 mounted 15 in a side wall of the casing 14 and contiguously with chamber 17. An electrode 32 extends from the post 31 inwardly of chamber 17 and downwardly to a point adjacent the bottom of said chamber, adjacent the side thereof on which post 31 is disposed and adjacent to the partition 16. A lead 33 extends from the other post 26 to a post 34 mounted in cover 21 above chamber 17 and adjacent the opposite side thereof to the post 31. A corresponding electrode 35 connects 25 with an depends from the post 34 downwardly through chamber 17 to a point adjacent its bottom and is likewise disposed adjacent to partition 16 and in spaced apart relationship to the electrode 32. Wires 30 and 33 and the electrodes 32 30 and 35 are each provided with tubular casings 36 of insulating material.

Casing 14 is adapted to contain an electrolyte, designated 37, such as a solution of sodium chloride and water or mercury in an amount sufficient 35 to partially fill one of its chambers and which is adapted to flow through opening 19 when casing 14 is tilted or rocked endwise with the opening 20 functioning as the vent between the two chambers.

Referring particularly to the diagrammatic view, Figure 7, the switch heretofore described is especially adapted for use with electric lights, and may be connected in any suitable circuit therewith as by means of the wires 38 and 39 which 45 extend from the two posts 26 to the posts 40 and 40', respectively, mounted in spaced apart relationship in a side wall of the box 10, the post 40 being connected by means of a lead wire 41 to one side of a source of electric current 42, the 50 opposite side of which is connected by the lead wire 43 to one of the contacts of a lamp bulb 44. A lead wire 45 extends from the post 40' to the second contact of the lamp bulb 44. Lead wires 41 and 45, as illustrated in Figure 1, are adapted 55 to extend through an opening 46' in the side of box 10 and lead wires 41, 43 and 45 are likewise enclosed in tubular insulating casings 36.

Secured to and projecting upwardly from one of the stub shafts 15, adjacent its free end, is an 60 arm 46 which is split and bent at its free end to provide the outwardly projecting apertured ear 47 and the inwardly projecting apertured ear 48. Ear 48 is adapted to be connected to the end 49 of a rod 50 the opposite end of which extends outwardly through an opening 51 in the side of the box 10, said last mentioned end being provided with a knob 52. A contractile coil spring 65 is connected at one end to the opening in ear 47 and the opposite end of the spring, designated 53, is connected to the hook 54 mounted on the bottom of the box 10. A stop 55 is also mounted on the bottom of box 10 and projects upwardly therefrom to limit the movement of casing 14 in one direction, as best illustrated in Figure 2, in dotted lines.

In Figure 8 a portion of the electrode 35 is illustrated and as the structure of each of the electrodes 35 and 32 is identical it is to be understood that Figure 8 could equally well be a section of the free end of electrode 32. It will be noted 5 that the casing 36 of the electrode 35 terminates short of its free end and that the free or exposed end, designated 56, is enclosed in a piece of sponge 10 designated 57. By thus encasing the terminal ends of the two electrodes 35 the sparking which ordinarily occurs when a circuit is made or broken 15 between two electrodes and an electrolyte conductor is prevented so that the gas and fumes given off by the sparks will be eliminated. By eliminating this sparking the formation of any precipitate in the electrolyte 37 is prevented, the 20 tendency of which in time would interfere with the proper function of the time delay portion of the switch.

From the foregoing it will be seen that casing 20 14 and the member 23 supported thereby are pivotally mounted for endwise rocking motion so that in one position chamber 18 is lowermost, while in the other position chamber 17 is lowermost, and the casing 14 and member 23 are intended and adapted to be swung to and from said positions by projecting and retracting rod 50. Spring 53 moves past the axis of the shafts 15 during the movement of the casing 14 from its position as seen in Figure 3 to its position as seen 30 in Figure 4, so that said spring is thus moved past its dead center and will thereby operate to hold casing 14 in either of the aforementioned positions. Knob 52 by engagement with the outer side of the box 10 limits the movement of casing 35 40 when it is tilted in the direction as seen, in Figures 2 and 3, while the stop 55 limits its movement when tilted in the opposite direction, and it will be noted that in this last mentioned position the casing is tilted at a slightly greater angle 45 toward the vertical so that the electrolyte 37 is held in the end of the chamber 17 and away from the electrodes 32 and 35, as best seen in Figure 4.

When casing 14 and the member 23 are tilted in the position as seen in Figure 3, the circuit from the source 42 to the lamp bulb 44 will be broken or open as the slidable contact 29 is out of engagement with the contact 25 and electrolyte 37 is in chamber 18 and out of contact with the electrodes 32 and 35 so that the circuit will be 50 open as in the diagrammatic view, Figure 7. In this position rod 50 will be in the position, as seen in Figure 2, so that when it is desired to light bulb 44 rod 50 is retracted to swing casing 14 to its dotted line position as seen in Figure 2, and as 55 illustrated in Figure 4. This movement will tilt the member 23 in the opposite direction so that the rods forming the sliding contact 29 will slide outwardly of the tubular portion 28 of contact 27 until they engage contact 25 to bridge the space 60 between said contact and the portion 28 of contact 27 to complete a circuit through the electric source 42 and the lamp bulb 44 to energize the bulb. When in this position, the electrolyte 37 will drain through opening 19 into chamber 17 65 and be contained in one end thereof, as seen in Figure 4. When rod 50 is again moved to its off or projected position, as seen in Figure 2, the electrolyte 37 will be contained in chamber 17, in the manner as illustrated in Figure 5 so that 70 even though the sliding contact 29 has moved out of engagement with contact 25 to break the connection between said contacts and contact 27, contacts 25 and 27 will still be connected by means of the electrodes 32 and 35 and their leads 75 30.

and 33, respectively, and the electrolyte 37 to maintain the circuit through lamp bulb 44 and the electric source 42 until the electrolyte 37 has drained into chamber 18 and out of contact with the ends 56 of the electrodes, when the circuit will be broken. It will thus be seen that the bulb 44 will remain energized for a certain predetermined period after the switch control rod 50 has been moved to its off position so that the operator of the switch will have time to leave the room or area which is lighted by bulb 44 before the light is extinguished. Obviously, this period can be varied by increasing or decreasing the amount of the electrolyte 37 and/or by varying the size of the opening 19.

Various modifications and changes in the precise construction and arrangement of the switch, comprising the invention, are contemplated and may obviously be resorted to, and the right is therefore expressly reserved to make such variations and changes in the construction and arrangement of the parts forming the invention as do not depart from the spirit and scope thereof as hereinafter defined by the appended claims.

25 I claim as my invention:

1. An electric switch comprising a hollow body portion provided with a transverse perforated partition dividing said body portion into chambers, means pivotally mounting said body portion intermediate of its ends, means for manually rocking said body portion on its pivot, a switch member disposed on said body portion and provided with spaced contacts at the ends thereof, a movable contact member slidably engaging one of said contacts and movable into engagement with the other contact when said switch member is tilted in one direction, electrodes extending from said spaced contacts into one of said chambers, said electrodes being spaced from each other, and an electrolyte partially filling said body portion and adapted to seep through said perforated partition to drain from the chamber in which said electrodes are disposed to open a circuit completed through said electrodes.

45 2. A switch as in claim 1, said electrodes being provided with insulation extending to a point adjacent their free ends, and said free ends being embedded in sponge elements.

3. A switch comprising a closed container provided with a centrally disposed transverse perforated partition dividing the ends of said container, an insulated member mounted on said container and disposed in a plane parallel to the plane thereof, said insulated member being provided with spaced contacts, one of said contacts having a tubular portion extending substantially the length of said member, a contact element slidably mounted in said tubular portion to engage said other contact when said member is tilted in one direction and to be moved away from said last mentioned contact when said member is tilted in the opposite direction, electrodes extending from said contacts and having their terminals disposed in spaced relationship in one end of said container, said container being partially filled with an electrolyte, and means for pivotally mounting said container intermediate of its ends whereby said container may be rocked to make and break the circuit between said first mentioned contacts, said electrolyte maintaining contact between said electrodes for a predetermined period after said sliding contact has moved out of engagement with one of said first mentioned contacts.

75 4. An electric switch comprising an insulated

tubular body portion, said body portion being pivotally mounted to rock endwise, spaced stationary contacts mounted in the ends of said body portion, one of said contacts having a tubular portion extending partially through said body portion, a sliding contact mounted in said tubular portion and constantly in contact therewith, said sliding contact being movable by the rocking movement of said body portion to move into and out of engagement with said other stationary contact to make and break a circuit between the stationary contacts, a container pivotally mounted intermediate of its ends and supporting said tubular body portion, said container having chambers at its ends, passages connecting said chambers, an electrolyte in said container adapted to flow through said passages into either of said chambers, and spaced electrodes extending into one of said chambers and connected to said stationary contacts for completing a circuit therebetween when said tubular body portion and container are tilted to move said sliding contact to an open position, said electrolyte draining from the chamber containing said electrodes, when the switch is in an open position, to open the circuit therethrough after a predetermined period.

5. An electric time delay switch comprising a container, a switch mounted thereon and having fixed stationary contacts and a movable contact slidably mounted to move into and out of engagement with one of said stationary contacts to make or break a circuit therebetween, electrodes extending from said stationary contacts into one end of said container, said container being provided with an electrolyte, passages connecting the ends of said container, means for rocking said container endwise to move said sliding contact to an open or closed position, said electrodes being disposed in the high end of said container when said sliding contact is moved to its open position, with their ends submerged in the electrolyte to complete a circuit through said stationary contacts, said electrolyte draining from said end through the passages to break the electric connection between said electrodes after a predetermined interval.

6. A time delay switch comprising a switch member including spaced fixed contacts and a movable contact, means for actuating said movable contact to make and break a connection between said fixed contacts, electrodes projecting from said fixed contacts, a container adapted to hold an electrolyte into which said electrodes extend, said container being actuated by said means for moving the electrolyte into contact with said electrodes when said movable contact is out of engagement with one of said fixed contacts to maintain a circuit through said fixed contacts for a predetermined period.

7. A switch comprising spaced fixed contacts, a movable contact, actuating means for moving said movable contact into and out of engagement with one of said fixed contacts to break a connection therebetween, electrodes extending from said fixed contacts, an electrolyte substance, and means containing said electrolyte substance movable by said actuating means for bringing said substance temporarily into engagement with said electrodes simultaneously with the movement of said movable contact out of engagement with one of said fixed contacts whereby a circuit will be maintained thereafter for a predetermined interval.

8. A time delay switch comprising spaced fixed

- contacts, a movable contact member, means to actuate said movable contact member to make and break a connection between said fixed contacts, electrodes extending from said fixed contacts, and means adapted to contain an electrolyte and to be actuated by said first mentioned

means to move said electrolyte into temporary engagement with said electrodes when the connection between said fixed contacts and movable contact member is broken.
